UNITED STATES PATENT OFFICE.

JESSE THOMAS CAMPBELL, OF ELBRIDGE, TENNESSEE.

SANITARY CHURN.

1,344,022.

Specification of Letters Patent. Patented June 22, 1920.

Application filed May 6, 1920. Serial No. 379,335.

To all whom it may concern:

Be it known that I, JESSE THOMAS CAMPBELL, a citizen of the United States, residing at Elbridge, in the county of Obion and State of Tennessee, have invented a new and useful Sanitary Churn, of which the following is a specification.

The device forming the subject matter of this application is a churn, and one object 10 of the invention is to provide a churn in which the cream may be housed securely and in a sanitary way, beyond the reach of flies and other insects.

Another object of the invention is to provide novel means whereby the cream may be cooled or heated, as occasion may demand.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in longitudinal section, a device constructed in accordance with the invention; Fig. 2 is a cross section on the 35 line 2—2 of Fig. 1; and Fig. 3 is a top plan showing the stopper.

The device forming the subject matter of this application comprises a body 1 provided with a bottom 2. A tube 3 upstands 40 from the bottom 2 and defines a cream compartment 4 and a chamber 5 about the compartment 4. An annular lid 6 is supported on the upper end of the body 1 and on the upper end of the tube 3 and constitutes a 45 closure for the upper end of the chamber 5. There is an opening 7 in the lid 6, the opening communicating with the chamber 5. The opening 7 is closed by a door 8 pivoted at 9 to the lid 6 to move parallel thereto. A 50 funnel-shaped cap 10 is provided, the same having a shoulder 11 resting on the lid 6, the shoulder merging into a flange 12 which fits in the upper end of the tube 3 to hold 55 the cap 10 in place against lateral movement. The numeral 12 denotes a dome-like top supported on the lid 6 in alinement with

the body 1, the top 12 having a marginal flange 14, which, coöperating with the body 1 prevents the top from moving laterally with respect to the body. The top 12 terminates in a neck 15 having an opening 16. A dasher operates in the cream compartment 4. The dasher may be variously constructed. It may embody a disk-like foot 17 having openings 18, a tubular socket 19 being secured to the foot. A rod 20 is received slidably, for adjustment, in the socket 19 and is connected thereto by a pin 21 or the like. The handle formed by the parts 19 and 20 extends upwardly through the 70 funnel-shaped cap 10 and out of the dome-shaped top 12. The construction is such that the length of the dasher handle may be varied at will, since the rod 20 may be telescoped more or less into the socket 19 and 75 be held at any adjusted length by means of the pin 21. A bail 30 is pivoted in ears 31 carried by the sides of the body 1, the bail being supplied with an intermediate handle 32. There is an opening 34 in the body 1, 80 forming an exit for the material in the chamber 5, the opening 34 being controlled by a closure plug 35.

In practical operation, either cold or hot water may be inserted into the chamber 5 85 by way of the opening 7, the door 8 being closed. The cap 10 is mounted in place, the top 12 is placed as shown in Fig. 1, and the churning operation is proceeded with. The plug 35 may be withdrawn to permit the 90 contents of the chamber 5 to drain away. While the cream is being churned, hot water ordinarily is placed in the chamber 5, and after the churning operation has been concluded, the hot water may be drained away 95 through the opening 35, cool water being substituted. An examination of Fig. 1 of the drawings will show that the churn is so constructed that it will be thoroughly sanitary, in that all parts of the churn may be 100 separated readily for cleaning, and further, on account of the fact that flies and other insects cannot gain access to the cream. Should the cream splash upwardly during 105 the churning operation, the cream will be received by the funnel-shaped cap 10 and will be returned to the cream compartment 4.

Having thus described the invention, what is claimed is:—

1. A churn comprising a body provided 110 with a tube defining a cream compartment and a chamber about the cream compart-

ment; an annular lid constituting a closure for the upper end of the chamber; a funnel-shaped cap constituting a closure to the upper end of the cream compartment; a 5 dome-like top supported on the body and inclosing the cap; and a dasher operating in the cream compartment and extended outwardly through the cap and through the top.

2. A churn comprising a body provided 10 with a tube defining a cream compartment and a chamber about the cream compartment; an annular lid extended between the tube and the body and constituting a closure for the upper end of the chamber, the lid 15 having an opening; a movable door con-

trolling the opening; a funnel-shaped cap supported on the lid and having a flange extended downwardly into the cream compartment; a dome-like top supported on the lid; and a dasher operating in the cream compartment and extended outwardly through the cap and the top. 20

In testimony that I claim the foregoing as my own, I have hereto affixed my signature in the presence of two witnesses.

JESSE THOMAS CAMPBELL.
